UNITED STATES PATENT OFFICE.

JETT G. K. BURNETT, OF PADUCAH, TEXAS.

CAPSULE-BOX CONTAINER.

Application filed February 10, 1922. Serial No. 535,490.

To all whom it may concern:

Be it known that JETT G. K. BURNETT, a citizen of the United States of America, residing at Paducah, in the county of Cottle 5 and State of Texas, has invented new and useful Improvements in Capsule-Box Containers, of which the following is a specification.

The object of the invention is to provide a 10 simple and convenient cabinet for support by the shelf of a prescription counter as a means of containing capsule boxes in convenient position for access by the pharmacists and of keeping the different sizes of 15 capsules in a classified relation to facilitate selection in the use thereof; and with these objects in view the invention consists in a construction and combination of parts of which a preferred embodiment is shown in 20 the accompanying drawings, wherein:—

Figure 1 is a perspective view of a capsule cabinet embodying the invention applied in the operative position to a prescription shelf or counter.

Figure 2 is a front elevation of the same.

Figure 3 is an inverted plan view thereof.

Figure 4 is a detail sectional view taken through one of the compartments of the cabinet.

Figure 5 is a detail in perspective of one of the capsule boxes or receptacles.

The device consists of a sheet metal receptacle having a plurality of separate compartments 10 of different cross sectional and 35 longitudinal diameters separated by partitions 11 and adapted for the respective reception of capsule boxes 12 of the commercial type in which they are received by the pharmacists from the manufacturer and which 40 boxes are ordinarily placed upon the counter or shelves in a separate or unrelated condition requiring the handling of the pharmacist in the selection of the size which he desires to use in the filling of a particular prescription. The compartments of the cabinet 45 forming the subject of this invention are open at their front ends with suitable finger notches 13 in the lower walls thereof to give ready access in grasping a capsule box contained therein, and the different compart-

ments are of relatively different sizes to accommodate the capsule boxes corresponding with the different sizes of capsules which are furnished therein, so that by replacing the capsule boxes in their proper 55 compartments of the cabinet for use, the sizes selected or required by the pharmacist in filling a particular prescription can be grasped immedately and without loss of time or confusion in making a selection and 60 without special reference to the designated or indicated sizes of the capsule as displayed on the container.

The cabinet is provided at its front edge with an upturned flange 14 designed to bear 65 against and lie in a co-extensive relation with the front edge of a shelf or counter 15 to which it may be attached by tacks 16 or equivalent fastening means, and at its rear edge the cabinet is also preferably provided 70 with a plurality of ears 17 for engagement by similar fastening means 18 driven into the underside of the shelf or counter.

The device is designed to occupy a position which otherwise is not utilized in connection with a prescription counter or cabinet in that its support beneath the shelf or counter does not interfere with the use of the shelf or counter for other purposes nor obstruct the use of the lower shelf or counter 80 ordinarily reserved for bottles and like receptacles which require a substantially horizontal rest or support.

Having described the invention what is claimed as new and useful is:—

A capsule cabinet for pharmacists' prescription counters having a plurality of dimensionally graduated compartments open at their front ends for the respective reception of capsule containing boxes and provided with means for attachment to the under surface of a shelf or counter consisting of an up-turned front flange for attachment to the front edge of a shelf or counter and rearwardly directed ears for attachment to 95 the under surface thereof.

In testimony whereof he affixes his signature.

JETT G. K. BURNETT.
